J. W. CONNERY.
CENTERING SQUARE.
APPLICATION FILED OCT. 5, 1914.

1,146,691.

Patented July 13, 1915.

UNITED STATES PATENT OFFICE.

JAMES W. CONNERY, OF KEWANEE, ILLINOIS.

CENTERING-SQUARE.

1,146,691.

Specification of Letters Patent.

Patented July 13, 1915.

Application filed October 5, 1914. Serial No. 865,080.

To all whom it may concern:

Be it known that I, JAMES W. CONNERY, a citizen of the United States, residing at Kewanee, in the county of Henry and State 5 of Illinois, have invented certain new and useful Improvements in Centering-Squares; and I do declare the following to be a full, clear, and exact description of the invention, such as will enable others skilled in the art 10 to which it appertains to make and use the same.

My invention relates broadly to improvements in metal workers' tools, and more particularly to devices for determining the centers of cylindrical bodies. Heretofore, a tool has been provided for this purpose, comprising a pair of diverging rigidly connected arms, and a blade projecting centrally between the two arms. It has been 20 found that rough usage often causes the arms to be bent or warped to such an extent as to prevent the tool from being accurate in its work. It is to overcome this most objectionable feature, that I have provided 25 my improved centering square which is equipped with a pair of diverging arms, one being pivoted to the other, means being provided whereby the pivoted arm may be locked against movement. By this means, 30 any inaccuracy in the instrument may be easily corrected.

With the above and minor objects in view, the invention resides in certain novel features of construction and combination herein 35 described and claimed and shown in the drawings wherein;

Figure 1 is a side elevation of a tool constructed in accordance with my invention; Fig. 2 is an end view thereof; Fig. 3 is a 40 vertical transverse section taken on the line 3—3 of Fig. 1; Fig. 4 is a longitudinal section as seen on the line 4—4 of Fig. 2; and Fig. 5 is a transverse section taken along the 45 plane of the line 5—5 of Fig. 4.

In the accompanying illustration, the numeral 1 designates a blade which is provided with a longitudinal groove 2 in one of its sides, and with graduated scales 3 along its opposite side edges. Slidably mounted upon 50 the blade 1 is a head 4 which may be of any appropriate design and which is provided with a pair of upright grooves 5 on opposite sides of the slot 6 through which the blade 1 passes. These grooves are provided for the 55 reception of a cylindrical head 7 of a locking bolt 8, which rises through a boss 9 on the

upper side of the head, and which is provided with a depending finger having a lug 10 on its lower end, said lug being located within the groove 2, whereby when a clamp- 60 ing nut 13 upon the upper end of the blade 8 is tightened, the head and blade will be held against relative movement.

Projecting from the head 4 and lying in the same plane therewith, is a rigid arm 14, 65 to the inner end of which the bifurcated end 15 of an adjustable arm 16 is pivoted, said arm 16 being shown as disposed in the same plane with the head and the rigid arm 14, and as projecting at an angle from the 70 latter. The arm 16 carries one or more ears 17 on its rear side, to which an adjusting bolt 18 is pivoted, said bolt passing loosely through an opening 19 in the lower end of an ear 20 which depends from the lower 75 side of the head 4, and receiving a pair of nuts 21 and 22 on opposite sides of said car. By this means, the arm 16 may be adjusted toward or away from the arm 14, by proper manipulation of the nuts 21 and 22, after 80 which said nuts may be tightened, thereby locking the arm 16 in adjusted position. It will be readily understood that various inaccuracies in the device may be positively overcome by making adjustments as above 85 described.

With the parts in working position, the upper edge of the blade 1 projects centrally between the arms 14 and 16, whereby when said arms are positioned upon a cylindrical 90 body, as seen in dotted lines in Fig. 1, said upper edge of the blade will represent the exact center of the body in one direction, it being understood that the tool is turned substantially 90° to locate the center in the 95 opposite direction.

From the foregoing description taken in connection with the accompanying drawings, it will be seen that I have provided an extremely simple tool for carrying out the 100 objects of the invention, yet one which will be highly efficient in operation.

In the preceding description, I have used the terms upper and lower, these terms being readily applicable to the device, as illustrated in the drawings, but it will be understood that the device need not be employed in the exact position illustrated but may be turned in any appropriate manner for accomplishing the best results.

I claim:

1. A tool comprising a head, a rigid arm

105

110

projecting therefrom in the same plane therewith, a movable arm disposed at an angle to the aforesaid arm and lying in the same plane therewith, an ear projecting from the head and located adjacent the movable arm, an adjusting bolt carried by the ear and the movable arm for adjusting the latter, and a blade carried by the head and projecting centrally between the fixed and movable arms.

2. A tool comprising a head, a rigid arm projecting therefrom and lying in the same plane therewith, a movable arm pivoted to the inner end of said rigid arm, said movable arm being disposed in the same plane with the rigid arm and being disposed at an angle to said rigid arm, and ear projecting from the head and having an opening, an adjusting bolt pivoted to the movable arm and passing loosely through said opening, lock nuts on said bolt contacting with the opposite sides of said ear, and a blade

carried by the head and disposed centrally between the fixed and movable arms.

3. The combination with a blade, of a head slideable thereon, a rigid arm projecting from the head and lying at an angle to the blade, a bifurcated movable arm straddling said blade and pivoted to the rigid arm, said bifurcated arm being likewise disposed at an angle to the blade, an ear projecting from the head and lying adjacent the movable arm, and an adjusting bolt carried by the ear and the arm for adjusting the latter and for locking the same against movement.

In testimony whereof I have hereunto set my hand in presence of two subscribing witnesses.

JAMES W. CONNERY.
